UNITED STATES PATENT OFFICE

FREDERICK C. KUMMER, OF MILWAUKEE, WISCONSIN, ASSIGNOR TO KERNER INCINERATOR COMPANY, A CORPORATION OF WISCONSIN

HOPPER AND CHECK

Application filed February 25, 1928. Serial No. 256,951.

This invention relates to hoppers and checks and has for an object to provide such a combination in which a hopper or similar closure may freely move to and from closing position and be checked and thereby silenced as it approaches the limit of travel in either direction.

Other objects and advantages will be more fully set forth and appear in the following 10 specification. One embodiment of my invention is illustrated in the accompanying drawings in which—

Figure 1 is a vertical section through a flue or duct illustrating a hopper and check 15 installed therein.

Figure 2 is a vertical section drawn to an enlarged scale through the check portion of the hopper and casing.

Figure 3 is an irregular section along the 20 line 3—3 of Figure 2.

Figure 4 is a section along the line 4—4 of Figure 2.

Like numerals refer to like elements throughout the drawings.

25 10 indicates generally a duct having the walls 10^a, in one of which is provided an opening 10^b. In this opening is mounted a rectangular frame or casing 11, having the outwardly and upwardly extending flange 11^a, and the side flanges 11^b at the lower portion of which is provided an ear 11^c. A pintle 12 extends between such ears and on this pintle is rotatably mounted a closure member 13, having a handle 14. Bosses 13^a 30 project from the inner face of the closure 13, and secured thereto is the front wall 15^a of a hopper 15 of conventional construction.

The upper edge 13^b of the closure 13 is extended slightly beyond the hopper 15 to contact with the upper flange 11^c of the frame 11 when in closed position, as illustrated in dotted lines in Fig. 1.

The bottom of the casing is provided with a cylinder or reservoir 11^d to which 45 leads a filling duct 11^e normally closed by the plug 11^f (see Fig. 2 for example). Reciprocably mounted in the chamber or reservoir 11^d is a plunger 16 having the internal recess or chamber 16^a shouldered at 16^b. 50 A duct or passage 16^c leads from the recess

16^a through the top of the plunger 16. A by-pass 16^e of relatively small cross-section is provided in one side of the plunger through the greater portion of its length but terminating short of the top to communicate 55 with a cross duct 16^f of larger sectional area, this latter duct 16^f leading to the passage 16^c. An adjusting set screw 18 is threaded into the top of the plunger 16 and may be projected more or less into the cross duct 60 16^f to vary the effective sectional area thereof for a purpose hereinafter described.

In the lower portion of the chamber 16^a is provided a coiled compression spring 20, which bears against the disk 21 at its upper end, and the bottom of the chamber or reservoir 11^d at its lower end. A ball check 22 is mounted between the disk 21 and the top of the chamber 16^a being of less diameter than the portion of the chamber in which 70 it is confined. The passage 16^c at its lower end is provided with a seat 16^g against which the ball 22 may be moved to close such passage.

The disk 21 is normally held against the 75 shoulder 16^b by the spring 20, and is provided with the non-circular opening 21^a therethrough, which is so constructed as to be partially but not entirely closed by the ball 22 in the position illustrated in Fig. 80 2 for example.

At the top of the reservoir or chamber 11^d is provided the gland cap 25, secured to the frame 11 by screws 26 or the like. This cap 25 projects downwardly into the reservoir 11^d, and is provided with the portion 25^a of a reduced diameter. A coiled compression spring 27 is mounted in the upper portion of the chamber 11^d around the cap portion 25^a as illustrated in Fig. 2. 85 90

A pin 30 is slidably mounted in the cap 25 and is of such length as to extend over the plunger 16, when the latter is in its lowermost position, through and beyond the cap 25. At its lower end is provided a cross-pin 30^a and a similar cross-pin 30^b is provided at its upper end. The hopper 15 at the bottom carries an impact pad 32 of any suitable material so located as to strike or impinge upon the upper end of the rod 100 105

30 when the hopper approaches closing position. A chain or other flexible member 34 is secured to the bottom of the hopper at one end, and at its other end to the cross-pin 30^b.

5 In the operation of the mechanism and apparatus described above, the closure 13 may be moved to or toward open position until the center of gravity of the closure 13 has passed over the vertical plane 10 through the pintle 12 when the closure and hopper may be released and the weight of the same will move them to open position illustrated in Fig. 1. As full open position is approached and the chain 34 fully extended, it will move with the rod 30 until the cross-pin 30^a strikes the spring 27, or if the spring be traveling therewith, until the spring strikes the cap 25. The spring will then cushion the final opening movement 15 of the closure and hopper. When the weight of the hopper and door are lifted from the rod 30 during the opening movement, the compression spring 20 will elongate and force the plunger 16 upwardly to the position illustrated in Fig. 1. During this movement the oil or other medium in the reservoir 11^d will flow with comparative freedom through the passage 16^e around the ball check 22 through the opening 21^a 20 in the disk 21 into the bottom of the reservoir. A certain amount of flow will also be permitted through the cross passage 16^f and the by-pass 16^e. The arrangement 25 and size of this passage and opening are such as to permit comparatively easy movement of the plunger 16 in such direction.

When the hopper and closure are closed they may be moved by hand until the center of gravity passes over the plane through 40 the pintle 12, or until the pad 32 strikes the top rod 30. The weight of the hopper and closure will then move the rod 30 downwardly, and such movement will be transmitted to the plunger 16. As soon as the 45 latter starts to move the ball 22 is moved against the seat 16^g and the oil or other medium entrapped beneath the plunger 16 is forced to escape through the by-pass 16^e and cross passage 16^f. These, being of relatively less cross-sectional area, restrict the 50 flow of the oil, and with the coiled spring 20, check or retard the final closing movement of the door and hopper, as will be apparent.

55 The device illustrated and described is particularly adaptable for use with incinerators or in other locations where a common duct or chute may serve for a plurality of apartments, in that it will check and cushion the final movement of the door and hopper toward opening or closing position and thereby greatly reduce or eliminate the noise resulting from the free contact which 60 has hitherto been had.

Should the oil or other medium in the reservoir 11^d require replenishing or replacement, this may readily be done through the opening 11^e, the open end of which is located beneath the level of the fluid and therefore 70 is not subjected to leakage.

75 The check means, being located in the frame or casing, may be readily assembled, tested and adjusted before installation of the hopper and closure, and in this manner a self-contained, compact device is obtained.

80 The flexible chain 34 or other flexible connecting means permits free and unrestrained movement of the hopper through the greater portion of the movement to and from open or closed position, so that no time is lost by the user in opening or closing the same, and the door and hopper may be manipulated as easily and with as little expenditure of time as in present day practice with uncheck devices of a similar character.

85 It will be apparent that the embodiment illustrated may be modified and altered, and I do not wish to be restricted to the form 90 shown and described, except as defined in the appended claims.

What I claim is:

95 1. In combination with a chute or the like having an opening in a wall thereof, a hopper member mounted in said opening and movable to and from open and closed positions, and yielding means connected to said hopper and a wall of said chute to check the hopper as it approaches either of 100 said positions while permitting free movement of said hopper intermediate its terminal approaches.

105 2. In combination with a chute or the like having an opening in a wall thereof, a hopper member mounted in said opening and movable to and from open and closed positions, yielding check means constructed and arranged to check said hopper as it approaches open or closed position, and a 110 flexible means operatively connecting said hopper to said check means and permitting free movement of said hopper throughout the greater portion of said movement.

115 3. A frame member having an opening 115 therein and mountable in an opening, a hopper pivoted in said frame and movable between positions opening and closing said frame opening, and yielding means connected to said frame and said hopper to 120 check said hopper as it approaches said open and closed positions while permitting free movement of said hopper intermediate its approaches to open and closed positions.

125 4. A frame having an opening there-through, a closure member mounted in said frame to open and close said opening, a hopper carried by said closure member, a yielding check means carried by said frame, and means operatively connecting said 130

hopper and closure to said check means to check the same as they approach either an open or closed position while permitting free movement thereof intermediate their 5 terminal approaches.

5. A frame having an opening therethrough, a closure member mounted in said frame to open and close said opening, a hopper carried by said closure member, a 10 yielding check means carried by said frame, and means operatively connecting said hopper and closure to said check means, said last named means comprising a flexible member permitting unrestrained movement 15 of said hopper and closure throughout the greater portion of its movement to and from open and closed position.

6. In combination, a frame member having an opening therethrough, a closure and 20 hopper movably mounted in said frame, said frame being provided with a reservoir, a plunger therein, means to resist movement of said plunger in said reservoir, and an actuating member extending from said 25 plunger outside of said reservoir and impacted by said hopper as the latter approaches one limit of travel, and flexible means connecting the hopper and actuating member whereby said hopper will be resisted by said plunger during its final movement in either direction.

7. In combination, a frame member having an opening therethrough, a closure and hopper movably mounted in said frame, said 35 frame being provided with a reservoir, a plunger therein, means to resist movement of said plunger in said reservoir, an actuating member extending from said plunger outside of said reservoir and impacted by 40 said hopper as the latter approaches one limit of travel, whereby said hopper will be resisted by said plunger during its final closing movement, a flexible member connecting said hopper and said actuating member, and means to resist movement of said 45 actuating member by said flexible member as said hopper approaches its other limit of travel.

8. In combination with a chute or the like 50 having an opening in a wall thereof, a hopper member mounted in said opening and movable to and from open and closed positions, and means coacting with said hopper to check the same as it approaches 55 either of said positions; said checking means comprising a cylinder, a plunger reciprocal therein, said plunger being provided with a relatively large passage therethrough, and a relatively restricted passage, 60 means to normally urge and move said plunger from one end of said cylinder, a check member associated with said plunger and mounted to close said relatively large passage in movement of said plunger toward 65 said end of said cylinder, and an actuating

member projecting from outside said cylinder thereto to contact with and move said plunger toward said end of said cylinder.

9. In combination with a chute or the like having an opening in a wall thereof, a hopper member mounted in said opening and movable to and from open and closed positions, and means coacting with said hopper to check the same as its approaches either of said positions; said checking means comprising a cylinder and a plunger reciprocal therein, a cap closing one end of said cylinder, said plunger being provided with an internal chamber and a passage of relatively large size leading therefrom through said plunger, said plunger being provided with a second restricted passage, a disk mounted in said chamber, a check member mounted in said chamber and movable between said disk and said first named passage, said check member being so constructed as to close said first named passage when moved to one end thereof, said disk being apertured in such wise as to permit flow of fluid past said check member therethrough, and an actuating member extending through said cap into said cylinder and movable with said plunger.

In testimony whereof, I have signed my name to this specification.

FREDERICK C. KUMMER.
